US0D1108427S

(12) **United States Design Patent** (10) **Patent No.:** **US D1,108,427 S**
(45) **Date of Patent:** **** Jan. 6, 2026**

(54) **MONITOR**

- (71) Applicant: **Samsung Electronics Co., Ltd.**, Suwon-si (KR)
- (72) Inventors: **Suan Choi**, Suwon-si (KR); **Bumho Chun**, Suwon-si (KR)
- (73) Assignee: **Samsung Electronics Co., Ltd.**, Suwon-si (KR)
- (**) Term: **15 Years**
- (21) Appl. No.: **29/945,789**
- (22) Filed: **Jun. 5, 2024**

(30) **Foreign Application Priority Data**

- Dec. 20, 2023 (KR) 30-2023-0052048
- (51) **LOC (15) Cl.** **14-02**
- (52) **U.S. Cl.**
USPC **D14/447**; D14/336; D14/374; D14/451
- (58) **Field of Classification Search**

CLAIM

The ornamental design for a monitor, as shown and described.

DESCRIPTION

FIG. 1 is a front perspective view of a monitor showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion 9 in FIG. 3; and,

FIG. 10 is an enlarged view of the encircled portion 10 in FIG. 8.

The evenly-dashed broken lines in the figures depict portions of the monitor that form no part of the claimed design. The dot-dash broken lines encircling portions of the claimed design that are illustrated in enlargements form no part of the claimed design.

1 Claim, 10 Drawing Sheets
